(57) **CLAIM**

We claim the ornamental design for a lens antenna, as shown and described.

DESCRIPTION

FIG. 1 is an enlarged perspective view of the lens antenna;

FIG. 2 is an enlarged perspective view thereof;

FIG. 3 is a top plan view of the lens antenna in an alternate position of use;

FIG. 4 is a front view thereof;

FIG. 5 is a bottom plan view thereof;

FIG. 6 is a rear view thereof;

FIG. 7 is a right-hand side view thereof; and,

FIG. 8 is a left-hand side view thereof.

In the drawings, the broken lines depict environmental subject matter only and form no part of the claimed design.
